UNITED STATES PATENT OFFICE.

CHARLES W. HUNTER, OF GARDINER, MAINE.

CAN-OPENER.

SPECIFICATION forming part of Letters Patent No. 695,055, dated March 11, 1902.

Application filed June 22, 1901. Serial No. 65,691. (No model.)

To all whom it may concern:

Be it known that I, CHARLES W. HUNTER, a citizen of the United States, residing at Gardiner, in the county of Kennebec and State 5 of Maine, have invented a new and useful Improvement in Can-Openers, of which the following is a specification.

This invention is an improved construction of can-opener, the object being to provide a 10 simple and inexpensive construction of can-opener which can be quickly and easily adjusted to fit different-sized cans, and one which will open the top of the can with an even cut, thereby permitting the can to be 15 used a second time.

Another object of the invention is to provide a can-opener which shall be absolutely safe in operation; and with these objects in view the invention consists in the peculiar 20 construction of the various parts and in their novel combination or arrangement, all of which will be fully described hereinafter and pointed out in the claims.

In the drawings forming part of this specification, Figure 1 is a perspective view showing the practical application of my invention. Fig. 2 is a vertical longitudinal section. Fig. 3 is a transverse section on the line 3 3 of Fig. 2. Fig. 4 is a detail perspective view of a handle and one clamping member. Fig. 5 is a perspective view of the other clamping member and shank. Fig. 6 is a detail view of the cutter. Fig. 7 is a slight modification. Fig. 8 is a transverse section 35 on the line 8 8 of Fig. 7.

In carrying out my invention I employ two clamping members A and B, which are adapted to clamp the upper opposite edges of the can. The member A comprises the plate A', 40 which is adapted to rest upon the top of the can, and the depending flanges A², which are adapted to grasp or clamp the side of the can, said flanges being moved substantially in the arc of a circle in order to snugly fit the side 45 of the can. A clamping member B comprises a plate B' and depending flanges B², the plate B' being adapted to rest upon the top of the can, while the flanges B² bear upon the side 50 of the can in exactly the same manner as the flanges A², but upon opposite sides. The clamping member A has a shank C integral therewith, said shank being connected to the

clamping member A by means of an offset or shoulder C', so that the shank C rests in the plane above the plate A'. The shank C is slot- 55 ted longitudinally for the greater portion of its length, as shown at C², and the underface of the shank is formed with a series of transverse serrations C³. The clamping member B is formed with an integral handle portion 60 D, said handle portion having openings D', and a plate B' also has an opening D². The shank C extends across the plate B' and also along the handle D, said shank and handle being connected by means of a bolt E and 65 wing-nut E'. The upper face of the handle D is provided with transverse serrations D³, which are adapted to mate with the serrations C³ upon the bottom of the shank, thereby securely holding the two clamping members A 70 and B in their adjusted positions. The cutter F comprises a blade F' and a shank F², said shank being arranged at a right angle to the blade and formed with an opening F³, through which passes the bolt G, said bolt 75 passing also through the opening D² and also through the longitudinal slot in the shank. A wing-nut G' is arranged upon the upper end for the purpose of securely connecting the cutter to the clamping member B. 80

In Figs. 6 and 7 I have illustrated a slight modification, in which the shank C⁴ works under the plate B' and between the flanges B². The handle D⁴ is also shown as separate from the clamping member, the bolt which serves 85 to secure the cutter serving also to connect the handle, clamping member, and shank. The serrations are also produced upon the upper side of the shank. The general operation, however, of the device is substantially 90 the same as in the construction shown in Fig. 1.

In practice I prefer to construct my can-opener of pressed steel; but it can be made of cast or malleable iron, if so desired. It 95 will also be understood that certain changes and modifications can be made without departing from the broad principles of my invention.

By having the clamping members A and B 100 adjustably connected and provided with the cutter arranged between them I am enabled to cut a circular opening in the top of the can quickly and easily and without the slight-

est danger of slipping. In operation the clamping members are adjusted to fit the can, and the tool is then placed upon the top of the can and the cutting-blade forced down 5 through the top. By means of the handle the blade is forced around the flanges, guiding the movement of the device, and a perfect circular opening will be made, thereby rendering the can capable of use a second time.

Having thus fully described my invention, what I claim as new, and desire to secure by Letters Patent, is—

1. A can-opener comprising the oppositely-disposed clamping members, one having a 15 shank integral therewith and the other having a handle member integral therewith, said shank and handle members being adapted to be secured together, and a cutting-blade attached to one of the clamping members, sub- 20 stantially as shown and described.

2. A can-opener comprising the clamping members, each clamping member consisting

of a blade and depending flanges, a shank integral with one of the clamping members, and the handle integral with the other, means 25 for connecting the shank and handle portions, and the cutting-blade attached to the plate of one clamping member, substantially as shown and described.

3. A can-opener comprising a pair of oppositely-disposed clamping members, each member consisting of a blade and depending flanges, a longitudinally-slotted shank integral with one clamping member, and an apertured handle integral with the other member, means for connecting the shank and handle, and the cutter adapted to be secured to the blade of one of the clamping members, 30 substantially as shown and described.

CHARLES W. HUNTER.
